UNITED STATES PATENT OFFICE.

THOMAS J. PRICE, OF OBLONG, ILLINOIS.

DRINKING-FOUNTAIN.

1,023,874.

Specification of Letters Patent. Patented Apr. 23, 1912.

Application filed October 12, 1911. Serial No. 654,281.

To all whom it may concern:

Be it known that I, THOMAS J. PRICE, a citizen of the United States of America, residing at Oblong, in the county of Crawford and State of Illinois, have invented certain new and useful Improvements in Drinking-Fountains, of which the following is a specification.

The present invention relates to sanitary 10 drinking fountains adapted to be attached to pumps and has for its purpose to provide a device of that character which is more simple in construction and neat in appearance than the structure disclosed in my co- 15 pending application for United States patent on a like invention.

The invention has for its further purpose to provide an apparatus which will be comparatively cheap to manufacture and one 20 which will require very little space for its installation.

The principle of operation in the present apparatus is the same as that set forth in my invention above referred to, and need 25 not therefore be given any precise detail in the present case.

With these and other objects in view the invention consists in the novel details of construction and combinations of parts more 30 fully hereinafter disclosed and particularly pointed out in the claims.

The invention is shown in its preferred embodiment in the accompanying drawing forming a part of this specification.

35 Referring to the construction in detail 1 designates a suitable reservoir of any appropriate design and which is closed at the bottom by a permanent closure 2 and at the top by a removable closure 3. The removable closure is adapted to be in closing 40 position at all times excepting when it is desired to gain access to the interior of the reservoir. A pipe 4 which enters into the reservoir has a screw threaded end 5 by 45 means of which said pipe is adapted to be connected with a pump or other source of water supply. The upper end 6 of said pipe is slightly curved and opens into the interior of the reservoir as will be understood. A 50 second pipe 7 incloses the pipe 4 to the end of compactness in construction, and said pipe 7 has a horizontal length section 8 which supports the drinking bowl 9 and the basin 10 as illustrated.

55 The pipe 7 has its lower end 11 closely fitting against the pipe 4 and at its upper

end said pipe is in communication with the reservoir. Said upper end of the pipe 7 which is at all times open defines the level of water to be maintained in the reservoir, 60 and in this capacity acts as an overflow, said overflow passing off through the pipe section 8 and a spigot 12 secured to said pipe section 8.

The drinking bowl 9 is secured to the pipe 65 section 8 through the medium of a relatively short pipe section 13 and the basin 10 which surrounds said bowl 9 is also secured to said pipe section 13.

A siphon pipe 14 which is contained substantially wholly within the pipe sections 7 and 8 has a siphon end 15 thereof entering into the reservoir 1 as shown in the drawing, and at its other end said pipe 14 communicates with and is adapted to deliver the 75 drinking water to the mouth bowl 9, as will be readily understood.

The siphon pipe 14 is provided with an aperture 16 for the purpose of drainage; and a similar aperture 17 is provided in 80 the pipe section 13. The aperture 17 drains the basin 10 through the pipe section 13 and the spigot 12.

It is obvious that those skilled in the art may vary the details of construction and arrangement of parts without departing from the spirit of my invention, and therefore I do not wish to be limited to such features except as may be required by the claims.

What I claim as new and desire to protect 90 by United States Letters Patent is:—

1. In a drinking fountain the combination of a reservoir; a pipe entering the reservoir and adapted to communicate with the source of water supply; a drinking bowl; a pipe surrounding the supply pipe and supporting said bowl; and a siphon pipe leading from the reservoir to the bowl, substantially as described.
2. In a drinking fountain the combination 100 of a reservoir; a pipe entering the reservoir and adapted to communicate with the source of water supply; a drinking bowl; a pipe having a vertical length inclosing the supply pipe and having a horizontal length supporting the bowl, said last named pipe providing an overflow for the reservoir; and a siphon pipe leading from the reservoir to the bowl, the discharge leg of said siphon pipe contained substantially wholly within 105 said second pipe, substantially as described.
3. In a drinking fountain the combina- 110

tion of a closed reservoir; a pipe entering the reservoir and adapted to communicate with the source of water supply; a drinking bowl; a pipe having a vertical length inclosing the supply pipe, and a horizontal length supporting the bowl; a spigot on said horizontal length providing an overflow with said second pipe; and a siphon pipe leading from the reservoir to the bowl and adapted to supply water to the latter, the discharge leg of said siphon pipe contained substantially wholly within said second pipe, substantially as described.

4. In a drinking fountain the combination of a closed reservoir; a pipe entering the reservoir and adapted to communicate with the source of water supply; a drinking bowl; a second pipe entering the reservoir and having a vertical length inclosing the supply

pipe, and having a horizontal length providing a support for said bowl; a spigot secured to the end of said horizontal length and providing with said second pipe an overflow for the reservoir; a siphon pipe leading from the reservoir to the bowl and adapted to supply water to the latter, the discharge leg of said siphon pipe contained substantially wholly within the second pipe; and an overflow pipe for the drinking bowl leading to said spigot, substantially as described.

In testimony whereof I affix my signature in presence of two witnesses.

THOMAS J. PRICE
